UNITED STATES PATENT OFFICE.

CARL E. ANDERSON, OF EAST ORANGE, NEW JERSEY, ASSIGNOR TO EASTERN TOOL & MFG. CO., OF BLOOMFIELD, NEW JERSEY.

BUTTON LOOP.

Application filed May 20, 1926. Serial No. 110,324.

This invention relates to an improved button loop and similar articles being particularly adapted for such loops as are used in fastening the straps of overalls to the buttons on the waist band, in fact, in any situation where quick attachment and detachment are necessary but in which the button is securely held even though the connected parts are relaxed.

10 The invention comprises a button loop which is made from one piece of wire and is formed so that it has at the top a supporting or suspending means for attaching the loops to a strap or the like, the wire then being formed into depending parts which form a loop for holding the shank of a button, the loop having a restricted entrance, the ends of the wire being secured to the opposed arms of the depending portion in a manner to permit their having a limited lateral movement to enable the restricted part of the loop to be temporarily widened.

15 The loop, of course, is so made that the head of the button can be inserted through it and then passed down so that the shank of the button will pass through the restricted entrance and into the button holding loop.

20 The invention is illustrated in the accompanying drawings in which I have shown various forms embodying the invention. In said drawings, Figure 1 is a front view and Figure 2 is a side view of one form of loop. Figure 3 is a front view of a modified form and Figure 4 is a side view of the form shown in Figure 3. Figure 5 is a front view of a still further modification and Figure 6 is a side view of the loop shown in Figure 5.

25 In describing the loop, it will, of course, be understood that the upper part is made to receive any element by means of which it can be suspended or to which it can be secured, but for clearness of description I will call it the strap receiving loop because normally it is adapted to receive a strap which is folded over the top bar and then is sewed or similarly secured.

30 In the form shown in Figures 1 and 2 the strap receiving loop comprises the strand 10, the ends of which are bent inwardly to form the strands 11 and the wire is then bent down to form the depending arms 12, each of which is formed at the bottom into a loop 13 which is the button receiving loop, these loops being normally substantially aligned and having an inwardly bent portion 14

forming a restricted entrance to the loop 13. These humps 14 are opposite to each other and form a symmetrical button holding part. Beyond the loop, each arm is extended and has its ends secured to the other arm in a manner to permit the respective arms to have enough side movement so that the loops 13 can swing in parallel planes when force is exerted by the button shank to widen the restricted opening of the button loop. In order to accomplish this, the ends of the arms 15 are folded or curled over the other arms.

35 In Figure 1, this is accomplished by bending the end of each arm into a loop 16 which can move laterally on account of the provision of the downwardly and outwardly inclined part 17 at the top of each of the arms 12 to enable a button to be inserted in the loop. The arms 12 and 15 are upwardly and outwardly inclined relative to the button loops 13 and at a sufficient angle to permit the easy insertion of a button between them. In Figures 3 and 4, I show a similar construction with the difference that, as will be noted in Figure 1, one strand lies in front of the other for its full length, while in Figure 3 the upwardly extending arms 15 are more vertically disposed and one of them is bent as at 18 so that they both extend upwardly on what will be called the back of the loop.

40 In Figures 5 and 6 I show a type of loop in which the arms that extend downwardly are arcuate as at 19 and form loops 20 at the bottom, the hump 21 of each arm being formed beyond the loop. The ends 23 of the arms provide for movement by reason of the loops being elongated and thus allowing the limited movement of the arms.

45 In these constructions it will be noted that the opening of the loops is easy as the arms 12 and 15 in Figures 1 to 4 and the arms 19 in Figures 5 and 6 move with the top part of the arms as a fulcrum or base of movement. This provides for easy leverage at the restricted part of the loop and the relatively loose looping of the ends of each arm to the other provides further flexibility of movement.

50 The loop is shown as made of round wire but it will be evident that other forms of strands can be used if desired.

I claim:

55 1. A button loop made of a single piece of

wire bent to form a strap receiving loop at the top and having depending arms returned to form a button holding loop with a restricted entrance, the arms each having its end secured in limited movable contact with the other beyond the button receiving loop.

2. A button loop comprising a single piece of wire bent at the top to form a strap receiving loop and then bent outwardly on both sides and then downwardly and inwardly and at the bottom formed into sub-

stantially aligned button receiving loops with a restricted opening, the ends of the wire beyond the button receiving loops extending to the outwardly extending portion 15 of the other and loosely looped thereover to permit limited side play of the said loops and the adjacent parts.

In testimony whereof I affix my signature.

CARL E. ANDERSON.
